UNITED STATES PATENT OFFICE

EDGAR A. GILLINDER, OF PHILADELPHIA, PENNSYLVANIA, ASSIGNOR TO GILLINDER & SONS, INC., OF PHILADELPHIA, PENNSYLVANIA, A CORPORATION OF PENNSYLVANIA

ILLUMINATING SHADE

Application filed July 15, 1925. Serial No. 43,670.

My invention relates to a new and useful improvement in illuminating glassware and it relates more particularly to a novel improvement in glass lamp shades whereby the general appearance and the artistic effects of a silk shade may be closely simulated so as to give the appearance of a silk shade by transmitted light, when the shade is illuminated.

With the above ends in view, my invention consists of a glass shade of any desired shape and formed of a clear crystal glass, having preferably a series of substantially parallel and substantially uniform corrugations or alternate ridges and furrows extending over its surface which represent the folds or pleats of a fabric, which may be omitted if desired, and having an outer glazed surface and an inner dull surface, and an inner coating of a suitable coloring material of any desired color. I may also, if desired, provide protruding beads extending transversely of such corrugations and colored with different pigment thereby simulating the colored braids on such shade.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Referring to the drawings:—

Figure 1, represents an elevational view of a novel shade embodying my invention.

Figure 2, represents a section on line 2—2 of Figure 1.

Referring to the drawings in which similar numerals of reference indicate corresponding parts.

1 designates a glass shade embodying my invention, supported by means of a metal shade holder 2, of any suitable construction and having positioned within it a suitable electric incandescent bulb 3. A series of parallel corrugations or alternate ridges and

furrows 4 are provided throughout the surface of the shade, as shown in the figures, which are of a size or width depending on the size of the shade, so as to simulate the folds or pleats of a fabric drawn taut longitudinally of such pleats or folds, upon concealed metallic frame, as is commonly the practice.

The outer surface 5, of the shade, is glazed so as to produce a reflecting surface while the inner surface 6 thereof is of a dull finish and carries a coating 7 of any suitable pigment or coloring matter, applied thereto in any suitable manner. The glass used for this purpose is preferably a clear colorless crystal glass, and the shade is die pressed and preferably of the contour of a truncated cone. The corrugations are preferably made slightly irregular or of slightly varying widths, so as more closely to simulate the irregularities of the pleats and folds of a silk shade.

By this novel combination in a glass shade, of a series of corrugations and an outer reflecting surface and the inner dull surface carrying a coating or layer of pigment, there is obtained a glass illuminating shade, having the general appearance and artistic effect of a silk shade, when light is transmitted therethrough, from within the shade. This effect, is a result of this novel combination of features, and is produced by the reflection and refraction of the light passing through the glass, augmented by the outer corrugated surface thereof.

If desired, there may be provided suitable upper and lower transverse protruding beads, such as 8 and 9, which are also preferably colored and provided with an outer stippled, or otherwise decorated surface, so as to simulate a colored braiding commonly employed on silk shades. The transverse beads 8 and 9 may be of the same or of a different color than the body of the shade. Since the beads 8 and 9 do not have the outer smooth reflecting surface, they will be quite different and will stand out in contrast to the corrugated surface of the shade, which is of a silky appearance.

It will now be apparent that I have devised a novel and useful illuminating shade which

embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent, is:—

15 An illuminating glass shade, having the contour of a truncated cone open at both ends with a series of alternate longitudinally extending ridges and furrows extending over its surface substantially parallel and of substantially uniform width, the outer surface of said shade being glazed and of a reflecting character while the inner surface thereof is dull and has a coating of pigment, and upper and lower annular stipple beads of different 20 diameters extending transversely across said furrows and ridges, whereby said shade will, by light transmitted through it from within, simulate a silk shade.

EDGAR A. GILLINDER.
